UNITED STATES PATENT OFFICE.

MELVIN J. FOYER, OF CHICAGO, ILLINOIS.

PNEUMATIC CONVEYER.

SPECIFICATION forming part of Letters Patent No. 652,960, dated July 3, 1900.

Application filed October 9, 1899. Serial No. 733,071. (No model.)

To all whom it may concern:

Be it known that I, MELVIN J. FOYER, a citizen of the United States, residing at Chicago, in the county of Cook and State of Illinois, 5 have invented a new and useful Improvement in Pneumatic Conveyers, of which the following is a specification.

My invention relates to an improvement in pneumatic conveying apparatus for use, 10 among other situations, in conveying cash-carriers in large stores and in similar locations.

My object is to provide simple and inexpensive means for reducing to a minimum 15 the power necessary to operate a pneumatic conveyer of this nature.

I accomplish my purpose by providing at the despatching ends of the conveying-tubes doors or valves controlling the admission of 20 air at said ends and electromagnets for holding said doors or valves open for a short period and by further providing in the vicinity of the delivery ends of said tubes circuit-breakers adapted to be moved by the carriers 25 in their passage through the tubes to temporarily deenergize the magnets and permit the doors or valves to close.

In the accompanying drawings, which illustrate a pneumatic conveying apparatus 30 equipped with my improvements, Figure 1 is a view, diagrammatic in its nature, showing the general arrangement of the entire apparatus; Fig. 2, a detail of a circuit-breaker employed; Fig. 3, a sectional detail of the despatching end of the incoming collecting-tube and its attendant parts, and Fig. 4 a 35 sectional detail of the despatching end of the outgoing distributing-tube and its attendant parts.

40 A represents a central or cashier's station; B, an outlying or salesman's station; C, an outgoing or distributing tube; D, an incoming or collecting tube; E, a blower having a high-pressure or delivery pipe E' and a low-pressure or suction pipe E²; F, an air-supply pipe connecting the pipe E' to the tube C adjacent to its despatching end; G, an exhaust or suction pipe connecting the pipe E² with the tube D adjacent to its delivery end; H, 45 a gate-like valve controlling the admission of compressed air from the pipe F to the tube C; I, an electromagnet for holding the valve

H open during the admission of air; J, a circuit-breaker at the station B for deenergizing the magnet I; K, a door-like valve controlling the admission of atmospheric air to the tube D; L, an electromagnet for holding the door K open during the admission of air therat; M, a circuit-breaker at the station A for deenergizing the magnet L, and N a 55 pressure-actuated device connected with the system (shown connected with the pipe E²) for controlling the speed of rotation of the blower.

The magnet I is shown connected with the 60 circuit-breaker J by wires a, and the magnet L is shown connected with the circuit-breaker M by wires b. The circuit-breaker J comprises a pivoted lever c, one end of which rests upon a contact-point c' and the other 65 end of which is pivotally joined to a vertical plunger c², which is normally held in its raised position by a spring c³ and which is provided at its upper end with a disk c⁴, located directly beneath the delivery end of the tube C in position to be moved by the carrier as it emerges from the tube. The circuit-breaker 70 M is similar in construction and is located beneath the delivery end of the collecting-tube D. 75

The construction at the despatching end of the distributing-tube C is shown in detail in Fig. 4. The gate H is provided with a stem d, which projects upwardly and is pivotally joined to one end of a link d', the latter being pivotally connected at its opposite end at a point d² to one end of an arm d³, which is rigid with and in one movement serves to operate a door d⁴, pivoted at d⁵. The arm d³ is provided with a rigid keeper or armature 80 d⁶, so located as to be brought into contact with the lower end of the core of the magnet I when the door d⁴ is closed by the central operator in sending out a carrier from the central station. The stem d preferably passes 85 through a cylinder or casing P, supported by a ring or bracket P' and containing a spring P², confined between the upper end of the casing and the piston-head P³ and which tends to keep the stem d and valve H de- 90 pressed. The piston-head P³ is of less diameter than its casing to permit the air to pass 95 said head, and the air serves to slightly cushion the valve in closing. The pipe F is 100

curved at its upper end and extends horizontally to receive the gate H, opening into the tube C at an enlargement C', which contains, above its junction with the pipe F, a 5 downwardly-opening valve e, which yields to permit the passage of a carrier, but which closes to prevent air from blowing out.

The construction at the despatching end of the collecting-tube D is shown in detail in Fig.

10 3. The door K is pivoted at f and is provided with an arm f', the upper end of which is connected by a link f² to the upper end of the plunger-rod f³, which projects through a casing Q and is provided inside said casing with 15 a piston-head f⁴ and a spring f⁵, which tends normally to close the door K.

The delivery end of the tube D is curved, as shown, and is in communication with the exhaust-pipe G at two points through a pipe 20 G', which forms a T with the pipe G. The end of the tube D is kept normally closed by a door g and spring g' bearing thereon.

The operation is as follows: Air is taken from the pipe E² and caused to accumulate 25 in the pipe E' by the blower, thus supplying the pipe F with compressed air and creating low pressure in the tube D. To send a carrier from station A, the operator inserts the carrier and closes the door d⁴. The carrier 30 drops past the valve e, and the closing of the door d⁴ raises the keeper d⁶ into contact with the core of the magnet I, at the same time lifting the gate H and admitting pressure to the tube C in the rear of the carrier. When 35 the carrier reaches the delivery end of the tube C, it drops out onto the disk c⁴ of the circuit-breaker J and interrupts the current of the circuit a, thereby deenergizing the magnet I and permitting the gate to close under 40 the action of the spring p³ in the casing P. To send a carrier from station B, the operator at said station lifts the door K, thereby bringing its metallic surface into contact with the core of the magnet L and then inserts the carrier. The latter is carried by atmospheric 45 pressure to the delivery end of the tube D, where it arrives with sufficient momentum to force open the door g and depress the disk of the circuit-breaker M, thereby deenergizing 50 the magnet L and permitting the door K to close.

It is necessary that the circuit-breaker be provided with a movable member extending into the path which the carrier traverses. It 55 is not necessary, however, that said member be located at the extreme delivery end of the tube, but only that it be located at a great enough distance from the despatching end of the tube to permit admission of sufficient air 60 to move the carrier properly to its destination. It is evident that where only sufficient air is admitted to the conveying-tubes to move the carrier properly the work done by the blower E in transferring air from the pipe E² to the 65 pipe E' is reduced to a minimum, which is the object sought.

The principle of my invention may be em-

ployed in systems which operate wholly by suction or reduction of pressure at the delivery ends of the tubes, in systems operating 70 wholly by compressed air, and, as in the instance shown, in systems which operate by both compressed air and reduction of pressure or partial vacuum.

The details of construction may be varied 75 as desired.

What I claim as new, and desire to secure by Letters Patent, is—

1. In pneumatic conveying apparatus, the combination of a low-pressure pipe, means 80 for maintaining a reduction of pressure therein, a conveying-tube connected toward its delivery end with said low-pressure pipe, a door at the despatching end of said tube controlling the admission of atmospheric pressure 85 thereto, an electromagnet for holding said door open during the admission of air, an electric circuit for said magnet, and a circuit-breaker in said circuit in the vicinity of the delivery end of said tube and provided with 90 a movable part located in the path of the carrier and serving when moved by the carrier to deenergize the magnet and permit the door to close, substantially as and for the purpose set forth. 95

2. The combination of an outgoing distributing-tube, an incoming collecting-tube, a blower in communication at its high-pressure side with the despatching end of said distributing-tube and at its low-pressure side with 100 the delivery end of said collecting-tube, a valve controlling the admission of air from said blower to said distributing-tube, an electromagnet, an armature for said magnet connected with said valve, a spring tending to 105 hold said valve closed, an electric circuit for said magnet, a circuit-breaker in said circuit near the delivery end of said distributing-tube, a door at the despatching end of said collecting-tube, means tending to hold said 110 door closed, an electromagnet for holding said door open during the admission of atmospheric pressure, an electric circuit for said 115 last-named magnet, a circuit-breaker for said last-named circuit located in the vicinity of the delivery end of said collecting-tube, and means connected with said apparatus for regulating the speed of said blower, substantially as and for the purpose set forth. 120

3. In pneumatic conveying apparatus, the combination of a conveying-tube, a low-pressure pipe connected with the delivery end thereof near the point of discharge of the carrier, means for maintaining a reduction of pressure in said pipe, a door at the discharge 125 end of said tube, means for holding said door normally closed, a door at the despatching end of said tube for controlling the admission of atmospheric pressure, means for holding said last-named door normally closed, an electromagnet for holding said last-named door open during the admission of air, an electric circuit for said magnet, and a circuit-breaker 130 for said circuit located in the vicinity of the

delivery end of said tube for deenergizing the magnet to permit the door at the despatching end of the tube to close, substantially as and for the purpose set forth.

- 5 4. In pneumatic conveying apparatus, the combination of a conveying-tube, means for producing movement of air therethrough, a valve controlling the admission of air to the despatching end of said tube, a spring tendencying to hold said valve normally closed, an electromagnet provided with a movable armature serving to hold said valve open dur-

ing the admission of air, an electric circuit for said magnet, a circuit-breaker in said circuit, located in the vicinity of the delivery end of said tube and in the path of the carrier, for deenergizing the magnet, and means for cushioning the movement of the valve in closing, substantially as and for the purpose set forth. 15
